OF MONTREAL, CANADA

ROCK DRILL

Application filed March 8, 1929. Serial No. 345,535.

This invention relates to new and useful improvements in rock drills and particularly to drills percussively driven and rotated and adapted for mine, quarry and other similar drilling operations.

The object of the invention is to provide a rock drill having a separable cutter head or bit so attached to the drill rod that the impact from the rock drilling machine is transmitted through the drill rod to the bit over a maximum area and on a plane at right angles to the direction of the blow.

A further object is to provide a rock drill with a removable bit attached to the drill rod by a member which will be accessible so that the bit may be quickly detached for repairs, inspection or other purposes.

A still further object is to provide a removable cutter head or bit so attached to the rod that the maximum diameter of the rod is less than the maximum diameter of the bit, such differences in diameter being sufficient to allow for clearance of the cuttings.

A still further object is to provide a bit of small dimensions and weight so that it can be economically manufactured, easily transported or carried to the drilling face and quickly and conveniently attached to the drill rod.

According to my invention, I provide a rock drill and a cutter head or bit held together by a connecting member, the head of which fits into a recess formed in the cutting face of the bit. The threaded shank of the connecting member passes through a hole in the cutter and engages with a threaded socket formed in the end of the drill rod. The length of the threaded socket is such that the end of the connecting member cannot contact with the bottom of the socket to transmit the percussive blows from the rock drill through the rod and bolt to the surface being drilled. The bolt or connecting member is adapted to draw the abutting surfaces of the drill rod and the bit together so that the percussive blows from the drilling machine are transmitted directly by the drill rod to the bit through their contacting faces which are at right angles to the direction of the said blows.

In the drawing which illustrates my invention.

Figure 1 is a perspective view showing a bit and a drill rod in assembled relation and made according to my invention. 55

Figure 2 is a part sectional elevation of the drill rod, bit and connecting member in assembled relation.

Figure 3 is a part sectional elevation showing the parts of the drill before assembly. 60

Figure 4 is an end view of the connecting member.

Referring more particularly to the drawing, 11 designates a drill rod which for illustrative purposes is shown hexagonal in cross section for substantially its full length merging into a rounded section towards the end 12. This drill rod has a central hole 13 extending through the full length of the rod for the passage therethrough of a cooling and lubricating agent. The face 14 of the rod is at right angles to the axis 15—15. Extending into the rod at the end 12 and from the face 14 is the threaded socket 16 adapted to engage with the threaded shank 17 of the connecting member 18. This member is provided with a central hole adapted to coincide with the hole in the drill rod. A bit 19 having a cutting surface 20 is provided with a recess 21 adapted to receive the head 22 of the connecting member. The head contacts with a shoulder 23 formed between the hole 24 and the recess 21. The shank of the connecting member passes through the hole 21 and engages with the threaded socket in the drill 70

rod. The depth of the head is preferably made smaller than the depth of the recess so that the head lies below the cutting face of the bit. The face 25 of the bit remote from the cutting face is drawn against the adjacent face of the rod by the connecting member and the length of said member is such that at no time during the operation of the drill can the end of the connecting member contact with the bottom of the socket. 85

The end of the bit abutting the drill rod is preferably of the same diameter as the rounded portion of the rod so that when the abutting faces are drawn together, they will present the maximum surface for transmit- 100

ting the percussive blows from the drilling machine through the drill rod directly to the bit. The maximum diameter of the cutting face of the bit is larger than the diameter of the drill rod, and the difference in diameter is such that cutting clearance is allowed.

This means that the wings of the bit have a gradual slope merging into the outer diameter of the drill rod so that an unimpeded 10 passage is presented for the egress of the cuttings made by the bit and there are no protrusions or shoulders which would interfere with the free working of the drill.

The connecting member or bolt may be 15 made comparatively small in diameter as its duty is only to hold the adjacent faces of the bit and rod together. The head of the connecting member may be provided with diametrically opposite flattened portions to 20 facilitate the assembly or dismantling of the drill. The connecting member may be made of metal, the main feature of which is its tensile strength. The rod may be made of a metal suitable for withstanding the shock 25 and fatigue due to the percussive and rotating action of the drilling machine (not shown). The bit may be made from a metal different from the rod as the main qualities of the bit is the retention of a cutting edge. 30 The bit is made small and light and is easily carried to the working face.

In operation, it will be seen that no 35 threaded portions are exposed which may become damaged through contact with the rock or the like. The rod is internally threaded so that the thread is protected from damage. The connecting members are light and inexpensive and very easily replaced. When the rod and connecting member are 40 provided with central holes, lubricating and cooling fluid may be fed to the drilling face.

In the drawing, a rock drill is shown but it will be evident that the connection may be used with substantially the same beneficial 45 results on other types of drills.

What I claim is:

1. A rock drill comprising a drill rod, provided with a longitudinally extending bore, the end of the bore adjacent to the bit engaging end of the rod being enlarged and internally threaded, a bit having a base adapted to engage the said end of the drill rod, said bit being provided with a central bore aligned with the socket in the drill rod, the outer end 50 of the bore being enlarged to form a central recess in the cutting face of the bit, and a bolt having a longitudinally extending groove passing through the bore of the bit with the head of the bolt countersunk in said 55 recess and the shank of the bolt threaded into the socket formed in the drill rod, but terminating in spaced relation to the bottom wall of the socket.

2. A rock drill comprising a drill rod provided with a longitudinally extending bore

and terminating at one end in a flat bit engaging face contained in a plane perpendicular to said bore, the end of the bore adjacent to said bit engaging face being enlarged and internally threaded, a bit having a base 70 adapted to flatly engage the said end of the drill rod, said bit being provided with a central bore aligned with the bore in the drill rod and a separately formed connecting member having one end fitted in the bore 75 of the bit and secured against rotation therein, the other end of said connecting member being threaded into the bore formed in the drill rod, the length of the portion of the connecting member projecting beyond the 80 base of the bit being less than the length of said enlarged portion of said bore.

In witness whereof, I have hereunto set my hand.
